UNITED STATES PATENT OFFICE.

CHARLES L. DEPOLLIER, OF NEW YORK, N. Y., ASSIGNOR TO DUBOIS WATCH CASE COMPANY, OF BROOKLYN, NEW YORK, A CORPORATION OF NEW YORK.

DETACHABLE STRAP-TERMINAL AND SAFETY-HOOK.

1,232,238.

Specification of Letters Patent.

Patented July 3, 1917.

Application filed April 28, 1914. Serial No. 834,949.

To all whom it may concern:

Be it known that I, CHARLES L. DEPOLLIER, a citizen of the United States, residing at New York city, in the county of Kings and 5 State of New York, have invented certain new and useful Improvements in Detachable Strap-Terminals and Safety-Hooks, of which the following is a specification.

This invention relates to a detachable 10 strap terminal and safety hook, and is especially designed for use in connection with strap watch bracelets whereby the interchanging of straps of different material and colors is readily and quickly accomplished.

15 The main object of this invention is to provide a simple, economical, durable and efficient device for securely and safely fastening the ends of a strap of any suitable material or desirable color to a watch or other 20 article, and at the same time allow the straps to be renewed or interchanged with great facility, at the will of the wearer or user.

Another object of the invention is to provide an improved detachable strap terminal 25 provided with a hook, and means connected therewith adapted to carry the strap end in such proximity to the hook as to practically lock the hook to the article to which it is attached, thereby preventing the accident 30 dental detachment of the said hook.

A further object of the invention is to furnish a detachable strap terminal device of 35 metal for removably securing straps to a bracelet watch, said device comprising means for safely securing the strap to the watch, and means whereby the straps may be quickly renewed or interchanged, the said device being of such style and shape as to be in keeping with the shape of the watch.

40 The foregoing and such other objects as may occur from the ensuing description are attained by the construction, combination, arrangement and location of the parts hereinafter more fully described, illustrated in 45 the accompanying drawings forming a part of this specification, and particularly pointed out in the claim appended hereto.

With reference to the drawings:

Figure 1, is a plan view of a strap watch 50 bracelet embodying my invention, showing straps broken away.

Fig. 2, is an inverted plan view of the construction shown in Fig. 1.

Fig. 3, is an enlarged longitudinal sec- 55 tional view of my improved detachable strap

terminal and safety hook showing in cross section the end of a strap secured thereto.

Fig. 4, is a transverse section of the device shown in Fig. 3, showing it hooked to one side of a portion of a watch case.

Fig. 5, is an enlarged perspective view of the detachable strap terminal and safety hook.

Fig. 6, is an enlarged plan view of a slightly modified form of detachable strap 65 terminal and safety hook.

Fig. 7, is a transverse section of the device shown in Fig. 6, and

Fig. 8, is an enlarged plan view of the strap bracelet buckle showing the buckle re- 70 moved from the strap.

Similar characters of reference are em- 75 ployed to designate like or the same parts throughout the several views of the drawings.

By reference to Figs. 1 and 2 of the drawings it will be seen that there is illustrated a top plan view and a reverse plan, respectively, of a strap watch bracelet, showing the watch A removably secured to the adjacent ends of the straps a, a', by my improved 80 detachable strap terminal and safety hook devices B and C, the device B being the preferred form, and C constituting a slightly modified form hereinafter more fully described. The strap a is provided at its outer end with a buckle D, the outer end of the strap a' having a series of perforations therethrough thus furnishing means whereby it will be understood the bracelet 90 may readily be secured to the wrist of the wearer.

The detachable strap terminal and safety hook device B consists of a transverse bar b provided at its central portion with an integral depending hook member c, and terminating in integral depending portions d and d', the lower end of the portion d' having hinged thereto a hollow tubular member e provided with an elongated slot e' and carrying within a slidably solid member f provided with a lateral projection g, which projects through said elongated slot and constitutes a stop for limiting the inward and outward movement of the member f carried by the said tubular member e.

The outer end of the member f is adapted to enter the opening h in the lower end portion d, whereby the members e and f are locked to the said transverse bar b, and near 110

the outer end of the member *f* is an outward integral projection *i* adapted to be engaged by the finger for manipulating the said member and causing the hinged member to 5 assume the unlocked and locked position.

As shown in Fig. 3 of the drawings the hollow member *e* carries a coiled spring within, which is adapted to rest against the inner end of the slidable member *f*, and 10 serves to force the latter outward and retain it in locked position. The looped end of the strap *a* surrounds the hinged member *e*, and the strap may be cut out at the rear central portion of the loop to allow the end 15 of the hook to substantially close up the space between the hinged member *e* and the hook *c*, as clearly shown in Fig. 4 of the drawings, thereby preventing the accidental unhooking of the detachable strap terminal 20 device from the watch when the hinged member is in its locked position.

When it is desired to renew or replace the old strap with a new one of a different color or material, it is simply necessary to engage 25 the projection *i* with the finger and force the slidable member *f* inwardly thereby unlocking the hinged member *e* from the bar *b* and then swing it outward to the position shown in Fig. 4, when the strap may be 30 slipped off and readily removed, and a new strap adjusted thereon, after which the hinged member may be swung back into the locked position shown in Fig. 3.

The modified form of my improved 35 detachable strap terminal and safety hook device shown in Figs. 6 and 7, shows a transverse bar *C'* having at its central portion an integral depending hook member *c'* and terminal integral projecting portions *m*, *m'*, 40 on a plane with said bar, the portion *m* having a member *n* hinged thereto, said member *n* being locked to the end *m'* of the bar *C'* by the slidable member *o*, engaging with an opening in the outer end of the projecting 45 portion *m'*, as clearly shown in Fig. 6, the terminal of the hook member *c'* resting in such close proximity to the hinged member as to prevent the accidental unhooking of the bar *C'* from the watch or other article 50 to which it may be attached.

Fig. 8 of the drawings shows an enlarged

view of the buckle *D* attached to the outer end of strap *a*, said buckle having a member *l* hinged to its inner end portion at *r*, and carrying a slidable member *s* adapted to 55 lock and unlock the hinged member in order that the strap may readily be renewed or exchanged.

It will be understood that my detachable strap terminal and safety hook may be attached to various articles, such as neck ribbons connected with lockets, for fobs where the silk becomes soiled and has to be renewed, for garters and numerous other articles where ribbons, elastic and other similar 65 materials are used for wear and it is desirable to renew or exchange the material employed.

Slight changes may be resorted to in the precise details of the construction herein described without departing from the spirit 70 of my invention.

Having thus described my invention what I claim and desire to secure by Letters Patent is:—

A detachable strap terminal and safety hook for strap watch bracelets comprising, 75 a metal bar having at each end thereof an integral right angle extension and an integral projecting hook member at its central portion, one of said extensions having an opening therethrough, and the other extension carrying a hinged hollow member at its outer end, said hollow member being provided with a solid slidable member adapted 80 to engage said opening and lock the hollow and solid members to the said bar, in combination with the looped end of a strap provided with a central opening in the loop, the terminal end portion of the hook member 85 being adapted to engage the opening in said loop and close the space between the hinged member and the end of the hook, to prevent the accidental unhooking of the watch from 90 the strap.

In testimony whereof I affix my signature in presence of two witnesses.

CHARLES L. DEPOLLIER.
